UNITED STATES PATENT OFFICE.

TERRY STAFFORD, OF TOPEKA, KANSAS, ASSIGNOR OF ONE-HALF TO
SMITH AUTOMOBILE COMPANY, OF MISSOURI.

VEHICLE-BRAKE.

No. 839,222.

Specification of Letters Patent.

Patented Dec. 25, 1906.

Application filed March 14, 1906. Serial No. 306,054.

To all whom it may concern:

Be it known that I, TERRY STAFFORD, a citizen of the United States, residing at Topeka, in the county of Shawnee and State of Kansas, have invented new and useful Improvements in Motor-Vehicle Brakes, of which the following is a specification.

My invention pertains to vehicle-brakes; and it contemplates the provision in a motor-vehicle of a simple, inexpensive, and durable brake of the friction-clutch type and one which may be depended on to hold without damage irrespective of the direction in which the vehicle is moving and which is equally reliable in releasing.

The invention will be fully understood from the following description and claim when the same are read in connection with the accompanying drawings, forming part of this specification, in which—

Figure 1 is a view, partly in plan and partly in horizontal section, of so much of a motor-vehicle as is necessary to illustrate the present embodiment of my invention. Fig. 2 is a detail transverse section taken in the plane indicated by the line 2 2 of Fig. 1 looking in the direction indicated by arrow.

Similar letters designate corresponding parts in both views of the drawings, referring to which—

A is the casing usually provided at the rear end of a motor-vehicle for the purpose of enclosing the equalizing-gear generally employed. B B are sleeves or tube-sections fixed to and extending outwardly from the said casing A and having diametrically-enlarged portions a at their outer ends on which are longitudinal splines b.

C C are the usual axles or axle-sections extending through the sleeves or tube-sections B and equipped with wheels D, and E E are the friction-clutches for braking the said wheels. The friction-clutches are identical in construction, and therefore a detailed description of the one shown at the left of Fig. 1 will suffice to impart a definite understanding of both. The said friction-clutch E at the left of Fig. 1 comprises a female member c, fixed to the adjacent wheel D and having a tapered rim d—*i. e.*, a rim gradually reduced in diameter outwardly—and a male member e, having a rim tapered in conformity to and arranged within the rim d of the female member, and also having a sleeve f, movable endwise

on the diametrically-enlarged portion a of the sleeve or tube section B and provided with an internal longitudinal groove g, receiving the spline b, Fig. 2, whereby it is held securely against turning on the said sleeve or tube section B. It will be readily apparent from the foregoing that when the clutch member e is moved outwardly it will coöperate with the member c on the wheel D in frictionally holding the said wheel to the sleeve-section B and against rotation. It will also be apparent that on the clutch member e being forced outwardly the result stated will be attained irrespective of the direction in which the wheel D is turning and without liability of any of the parts being impaired. It will further be apparent that there is no tendency of the male member e to bind in the female member c, and hence on the inward movement of the member e the release of the wheel is certain.

F is a T-lever fulcrumed at the middle of its head on the casing A and having a comparatively long arm or stem m. G is a rod connected to the said arm or stem m and designed to be connected with a hand-lever or other device (not shown) for actuating it, and H H are rods extending between and connecting the opposite ends of the head of lever F and the male members e of the two friction-clutches. By virtue of this construction great leverage is afforded, and hence when the rod G is drawn forwardly the clutch members e will be powerfully moved outward to fasten the wheels D to the sleeves or tube-sections B and hold said wheels against rotation. It will also be appreciated that by graduating the pull on the rod G the wheels D may be either locked against rotation or retarded in their rotation, as the exigencies of the case require.

It will be readily gathered from the foregoing that my improved brake entails the addition of but few parts and little weight to a motor-vehicle and that it is simple and reliable in operation and is not likely to be affected by dust, dirt, and the like.

Having described my invention, what I claim, and desire to secure by Letters Patent, is—

A motor-vehicle comprising a casing A, tubes or sleeve-sections fixed to and extending outward from said casing and having diametrically-enlarged portions at their outer ends, axle-sections extending through the

tubes or sleeve-sections and provided with wheels, female clutch members fixed to said wheels and having outwardly-tapered rims, complementary male clutch members splined on the enlarged portions at the outer ends of the sleeves or tube-sections and having outwardly-tapered rims arranged within and adapted to frictionally engage the rims of the female members, rods fixed to and extending inward from the male clutch members, a lever fulcrumed at the middle of its head on

the casing A and having the ends of its head connected to said rods and also having a comparatively long arm or stem.

In testimony whereof I have hereunto set 15 my hand in presence of two subscribing witnesses.

TERRY STAFFORD.
